[57] ABSTRACT

A divider construction for a paperboard container comprising an envelope and a handle having a grip portion, said grip portion of said handle being movable into and out of said envelope, said envelope including an anchor panel for said handle, said handle and said anchor panel each having a parting edge, said parting edge of said handle being in juxtaposed relation to said parting edge of said anchor panel, tearable joining means integrally formed with said handle and with said anchor panel joining said handle to said anchor panel characterized by a bar formation that joins said handle and said anchor panel, one end of said bar formation being spaced from the other end of the bar formation in the direction of the parting edges whereby when said handle is separated from said anchor panel in a direction across the direction of said parting edges, said bar is twisted and tears whereby said handle becomes separated from said anchor panel.

DIVIDER CONSTRUCTION

This invention relates to a divider handle construction for a paper board container of the type having a carrying handle that can be gripped and slid upwardly of the container from a retracted position within the envelope formation of the divider to an operative position where it can be used to carry the container. More particularly it relates to a divider handle construction in which the slideable carrying handle is formed integrally with but is severable from the stationary divider. It is concerned with the severable interconnection of the handle from the stationary divider.

Dividers of the general type under consideration are illustrated in U.S. Pat. No. 2,609,137. With dividers of this type, the carrying handle is formed integrally with the divider construction, but the interconnection is such that it can be manually broken by a user of the container who slides the handle upwardly of the divider. It has been usual to interconnect the handle to the divider construction by means of an intermittent cut. The handle is separated from the anchor panel of the container except at small spaced apart lengths which are designed to be broken by the handle lifting force.

One of the difficulties with divider handle constructions of this type is that the interconnection between the handle and the divider construction is sometimes difficult to break. It is not always possible to sufficiently reduce the strength of the interconnection by reducing the length of the uncut portions of the connecting line because if it is weakened sufficiently for easy breaking away, the handle tends to break off during the setting up of the container. The handle must be rigidly enough attached to the divider construction to withstand the folding operations in the manufacture of the container. At the same time it must be severable with a light upward force during use.

This invention has a construction for the interconnection of the handle and the divider construction that is easy to sever and at the same time gives the necessary strength to permit the container to withstand the normal stresses involved in the manufacturing operation.

With these and other objects in view, a divider construction according to this invention comprises an envelope and a handle having a grip portion, said grip portion of said handle being movable into and out of said envelope, said envelope including an anchor panel for said handle, said handle and said anchor panel each having a parting edge, said parting edge of said handle being in juxtaposed relation to said parting edge of said anchor panel. Tearable joining means integrally formed with the handle and with the anchor panel joining the handle to the anchor panel characterized by an elongated bar formation that joins said handle and said anchor panel, one end of the bar formation being spaced from the other end of the bar formation in the direction of the parting edge whereby when the handle is separated from the anchor panel in a direction across the parting edge the bar rotates about an end portion and tears across its width whereby said handle becomes separated from said anchor panel.

The invention will be clearly understood after reference to the following detailed specification read in conjunction with the drawings.

In the drawings:

FIG. 1 is a perspective view of the container in a set up position;

FIG. 2 is a sectional view along the line 2—2 of FIG. 1;

FIG. 3 is a sectional view along the line 3—3 of FIG. 1;

FIG. 4 is a sectional view along the line 4—4 of FIG. 3;

FIG. 5 is a schematic view of the initial stressing of the connecting bars as the handle is initially separated from the anchor panel;

FIG. 6 is a schematic view of the severed bars; and

FIGS. 7 to 9 inclusive are schematic view of alternative designs.

In the drawings, a container of the general type illustrated in U.S. Pat. No. 2,609,137 has been illustrated. It has a central divider with a retractable handle therein. When the container is initially formed by folding the hinged panels thereof, the handle is integrally connected to an anchor panel within the envelope of the divider for subsequent manual separation therefrom. The container is not illustrated in detail in this application and it will be appreciated that the particular container is illustrated only for the purposes of showing an envelope type divider that has a slideable handle therein.

FIG. 1 is a perspective illustration of a chip board container which has side walls 10, end walls 12 and a divider wall generally indicated by the numeral 14 which extends for the length of the container between the end walls 12. The container in the embodiment illustrated is formed from a series of hingedly connected panels as illustrated in U.S. Pat. No. 2,609,137. The divider construction generally indicated by the numeral 14 comprises two outer panels 16 joined at their upper edge by a fold line 18 which is cut away at its mid-section to provide an opening 20 for the passage of the gripping portion of the handle member 22. It will be noted that the handle member 22 has shoulders 24 adjacent its lower end which engage with and interlock with the inside of the fold line 18 to limit the extension of the handle 22 out of the envelope.

In the embodiment of the invention illustrated, the handle member 22 is formed by double plies 26 of paperboard which are each severably connected to an anchor panel 28 located between the outer panels 16 as will be described later.

As indicated above, the precise nature of the handle member 22 and the envelope which encloses it is not material to the invention. The invention is the manner of interconnecting the handle member 22 with the anchor panel 28 of the divider construction so that it can be easily severed and slid to an extended position in use.

The nature of a preferred manner of making this interconnection is illustrated in FIG. 4. The handle member 22 and the anchor panels 28 are interconnected along their respective parting edges by means of elongated bar formations 32. The respective members have a cut line between them except for the bar member. It will be noted that each bar formation joins with the handle member and with the anchor member and that the ends of the bar members are spaced apart from each other in the direction of the parting line 34 between the handle and the anchor members.

As the gripping portion of the handle member is pulled through the opening 20 in the top of the envelope

lope formation of the divider and slid from the envelope, the bars 32 are twisted at their end portions with the result that they tear transversely, usually adjacent one of the end portions. FIG. 5 is an illustration of the twisting motion that takes place in the connecting bars as the handle 22 is initially separated from the anchor panel 28. Numeral 29 is an arrow indicating the preferred grain direction of the paperboard.

As the bar is twisted due to the separation of the handle and the anchor panel one edge of the bar is compressed and the other edge is stressed in tension. Tear initiates at the edge that is under tension and proceeds across the bar as separation of the handle from the anchor panel continues. The tear tends to be in grain direction which preferably extends across the bar. The twisting action tends to take place at each end of the bar. The bar will tear adjacent one or the other end and not always at the same end in each instance.

FIG. 6 is an illustration of the severed pieces.

It will be appreciated that the parting line illustrated in FIGS. 4 to 6 is duplicated on each of the two plies of the handle.

It will be noted that the connecting bars 32 are in pairs and that one bar of each pair is located above the principal axis of the parting line and the other bar of each pair is located below the principal direction of the parting line. This avoids a tendency for the handle to fold at the parting line during assembly of the blank.

The form of the interconnection shown in FIG. 5 is not the only form and FIGS. 7, 8 and 9 illustrate some alternative forms of interconnecting bars.

In each case an elongated bar formation would join the parting edge of the handle member and the anchor portion of the divider assembly. In FIG. 7 the bar 36 would connect to the handle adjacent one end along its side edge and would connect to the anchor portion at its other end. In FIG. 8 the bar 38 is formed with an offset portion in its middle and would connect at one end with the handle and at its other end with the anchor. The embodiment shown in FIG. 9 has two bars 40 and 42 in juxtaposed relation each connected at one end to the handle and at one side adjacent its other end to the anchor.

In the case of each embodiment the one end of the bar formation is spaced from the other end of the bar formation in the direction of the cut parting edge of the anchor and panel whereby when the handle is separated from its anchor panel in a direction across the parting edge of the anchor panel the bars are twisted and tear across their width. Tearing stress is applied adjacent both ends of the bar but the break will occur at one end first depending on the design and on the nature of the pull applied to the handle. It is not necessary that the interconnection of the handle and anchor member be on two plies as illustrated. It could be on one ply only.

It will be noted that the bars illustrated in FIGS. 1 and 4 are arranged such that they will each swing in a counter-clockwise direction with respect to the anchor panel. This is a good arrangement, but a preferred arrangement would be to reverse the left of the pairs of bars so that the pairs rotate in opposite directions and

away from each other. In this way, the pairs of bars are stressed in tension to give an additional bar breaking force. For example, if the left handed pair of bars were changed so that the Z-shaped cut in the middle had its mid-arm sloping in the opposite direction, then upon lifting of the handle, the left handed pair of bars would twist clockwise and the right handed pair of bars would twist counter-clockwise. The two sets would twist away from each other to contribute to breakage of the bars.

The width of the bars will depend upon the strength of the paperboard. A width of about three thirty-seconds of an inch for chip-board having a thickness of 0.024 is satisfactory.

Modifications to the embodiments of the invention illustrated will be apparent to those skilled in the art. The divider construction can be formed integrally with the container as in the case of U.S. Pat. No. 2,609,137 or it can be separately formed for insertion into a container.

What I claim as my invention is:

1. A divider construction for a paperboard container comprising an envelope and a handle having a grip portion, said grip portion of said handle being movable into and out of said envelope, said envelope including an anchor panel for said handle, said handle and said anchor panel each having a parting edge, said parting edge of said handle being in juxtaposed relation to said parting edge of said anchor panel, tearable joining means integrally formed with said handle and with said anchor panel joining said handle to said anchor panel characterized by a bar formation that joins said handle and said anchor panel, one end of said bar formation being spaced from the other end of the bar formation in the direction of the parting edges whereby when said handle is separated from said anchor panel in a direction across the direction of said parting edges, said bar is twisted and tears whereby said handle becomes separated from said anchor panel.

2. A divider construction as claimed in claim 1 in which said joining means has a plurality of said elongated bar formations arranged in pairs, one bar of each pair being above the parting edges of said handle and said anchor panel and the other bar of each pair being below the parting edges of said handle and said anchor panel.

3. A divider construction for a paperboard container as claimed in claim 1 in which the grain direction of the paperboard extends across said bar formation.

4. A divider construction as claimed in claim 1 in which said joining means are spaced along said parting edge on opposite sides of the centre of said parting edge, the direction of twist of said bars of said joining means that results from the separation of said handle from said anchor panel being clockwise on one side of said centre and counter-clockwise on the other side of said centre with the bars separating whereby the direction of twist has a tearing effect on said bars as said handle is separated from said anchor panel.

5. A divider construction for a paperboard container as claimed in claim 2 in which the grain direction of the paperboard extends across said bar formation.
